UNITED STATES PATENT OFFICE.

JOHN H. CASTONA, OF MOSS POINT, MISSISSIPPI, ASSIGNOR TO CASTONA IMPROVED PROCESS CO., OF GULFPORT, MISSISSIPPI, A CORPORATION OF SOUTH DAKOTA.

TURPENTINE AND RESIN EXTRACTOR.

1,083,802.

Specification of Letters Patent.

Patented Jan. 6, 1914.

Application filed June 15, 1912. Serial No. 703,933.

To all whom it may concern:

Be it known that I, JOHN H. CASTONA, a citizen of the United States, residing at Moss Point, in the county of Jackson and 5 State of Mississippi, have invented new and useful Improvements in Turpentine and Resin Extractors, of which the following is a specification.

This invention relates to an extractor for 10 extracting turpentine and resin from resinous woods, the object of the invention being to provide an extractor which is simple of construction, permits of the ready and convenient introduction of a charge of wood 15 and the removal of the residue after extraction, and by means of which the material may be subjected to the action of steam and a solvent to effect the rapid and thorough separation of all of the available turpentine 20 and resin from the charge.

The invention consists of the features of construction, combination and arrangement of parts, hereinafter fully described and claimed, reference being had to the accompanying drawing, in which,

Figure 1 is a side elevation of an extractor embodying my invention. Fig. 2 is a central vertical transverse section of the same. Fig. 3 is a horizontal section on the line 3—3 30 of Fig. 2. Fig. 4 is a detail section illustrating a feature of construction.

Referring to the drawing, 1 designates an extracting cylinder or vessel, normally open at its upper end, and provided with spaced 35 imperforate bottom heads 2 and 3 forming an intervening steam chest or heating chamber 4. From this chamber leads a pipe 5 having a controlling valve 6, for a purpose hereinafter described. Arranged within the 40 cylinder 1 is an internal cylinder or cage 7, which is also open at its top, and is perforated throughout its sides and bottom portion. This cage 7 is adapted to contain a charge of suitably comminuted wood to be 45 treated and is of less length and diameter than the cylinder 1. At its upper end the cage 7 is held in spaced relation to the cylinder 1 by a band or ring 8, and bolts or screws 9 pass through the cylinder, cage, 50 and ring, and detachably secure the cage in position. The band is arranged sufficiently below the upper edges of the cylinder and cage to form an annular groove or recess 10 for the reception of a gasket or packing ring 55 11 of rubber or other suitable material.

By the described arrangement of the cage 7 within the cylinder 1, an annular intervening space 12 is provided for the discharge of the steam and extracted vapors from the wood through the perforated sides and bottom of the cage into the space 12, and thence through a vapor discharge pipe 13 having a controlling valve 14 to a suitable condenser, not shown, wherein the vapors are condensed and placed in condition for subsequent separation. Such arrangement of the cage 7 also provides a collection space or diameter 15 between the perforated bottom of said cage and the head 2, which space receives the separated resin dripping from the wood. A discharge pipe 16 having a controlling valve 17 communicates with said space 15, whereby the resin and any water of condensation which may remain in the cylinder may be drawn off.

After the cage 7 is filled with a charge of wood and inserted and secured within the cylinder 1, the top of the latter is closed by a hinged lid or cover 18, which lid or cover is provided with peripheral notches or recesses 19 to receive locking bolts 20 hinged to the body of the vessel 1 and provided with wing nuts 21 whereby the cover may be firmly clamped in position. Extending through the lid or cover is a pipe 22, having a controlling valve 23, and which is connected below the lid with a perforated spray pipe or coil 23, through which a hydrocarbon or other solvent may be introduced into the cage and sprayed upon the wood, so that it will percolate by gravity therethrough, to take up the volatile constituents of the wood not driven off by the heat.

Arranged centrally within the cage 7 and fixed at its lower end to the bottom thereof is a perforated steam supply pipe 24, which terminates just below the upper end of the cage and is provided at its upper and lower ends with plugs or other suitable closures 25, whereby the steam supplied to said pipe 100 will be caused to discharge laterally through the perforations therein so as to be uniformly and evenly distributed throughout the mass of the wood.

Arranged on opposite sides of the extractor are supporting brackets or standards 26 and 27 having bearing bushings 28 and 29 in which are journaled the outer ends of pipes 30 and 31. These bushings also receive steam supply pipes 32 and 33 respect 105 110

tively provided with controlling valves 34 and 35, said pipes being in respective communication with the pipes 30 and 31. The pipe 31 extends downwardly through the space 12 between the cylinder and cage and has its lower end 36 extending through the head 2 into the chamber 4 for the supply of steam thereto, while the pipe 31 extends across one side of the cage and communicates at its inner end with the vertical steam supply pipe 24. The extractor is adapted to be tilted from a vertical to a horizontal position and vice versa, on the outer ends of the pipes 30 and 31, acting as trunnions journaled in the bearing bushings 28 and 29, for convenience in filling and emptying the cage and inserting and removing different cages as occasion requires. This permits the cage which has been in use to be removed with the residuum and a filled cage to be inserted in its place, with greater economy of time and labor in extracting the constituents from successive charges of the material. Fixed to one of the bearing bushings is a sprocket wheel 36 connected by a chain 37 with the sprocket pinion 38 on the shaft 39, to which may be applied a crank handle or other suitable operating device, whereby the extractor may be conveniently tilted.

In operation, the cage 7, filled with a charge of comminuted wood, is inserted and secured within the cylinder 1, and the lid or cover 18 applied to hermetically seal the same. The valve 35 is then opened for the admission of steam through the pipe 31 into the perforated pipe 24, which steam is diffused by said pipe 24 evenly throughout the mass of wood, thus heating it to a high degree and driving off the volatile constituents which pass with the steam outward through the perforated walls of the cage into the spaces 12 and 13. The volatile constituents discharging with the steam are allowed to escape through the pipe 13, the valve 14 of which is opened at a proper period after the device is set in operation, while the resin drips through the perforated bottom of the cage into the collection space or chamber 15. After all the constituents of the wood which may be extracted by the action of steam, are driven off, the valve 23 is opened for the admission of a volatile hydro-carbon through the vapor 23, such solvent percolating downward through the mass of wood and extracting the remaining volatile constituents thereof, and finally being flashed into vapor therewith by the heat of the mass, the vapors discharging through the pipe 13 to a condenser, as hereinbefore described. After the extraction of the remaining volatile constituents of the wood by the solvent, the valve 34 is opened and steam is admitted through the pipe 30 into the chamber 4, whereby the bottom of the extractor is heated and the resin maintained in a liquid state

for ready recovery and discharge through the outlet 16. At the same time this steam admitted into the chamber 4 superheats the chamber 15 and a due proportion of the heat is transmitted to the body of wood, whereby the proportion of solvent remaining in a liquid condition in the wood is vaporized and driven off. During this operation of admitting steam to the chamber 4, the valve 6 may be left slightly open for the sole escape of steam through the pipe 5, thus keeping up a supply of steam to said chamber to maintain a desired degree of heat and prevent condensation of steam therein. Any water resulting, however, from the condensation of any portion of the steam during the last stage of the extracting operation may be withdrawn through said pipe 5, as will be readily understood. Preferably the pipe sections 32 and 33 are rigidly connected by a union 41 fixed to a main steam supply pipe 42, so that said pipes will be held from motion when the extractor is tilted.

From the foregoing description, it will be seen that my invention provides an extractor of simple construction, by which steam may first be employed to extract a large proportion of the volatile constituents, and a solvent then employed to extract the remainder of the constituents which cannot be extracted by the steam, and that the solvent may finally be driven off by steam admitted into the bottom chamber 4, whereby all of the available turpentine, resin, and other volatile constituents will be extracted in a simple economical manner.

At the end of the extracting operation, the extractor may be tilted to a horizontal position for the convenient removal of the waste matter and insertion of a new charge to be treated, so that the operation of treating successive charges of wood may be carried out in a practically continuous manner.

By the use of steam and a solvent, the volatile constituents of the wood are obtained in a highly pure condition, and may be readily and conveniently separated from the water of condensation and the solvent, so that the latter may be used over and over again.

Having thus fully described the invention what is claimed as new is:

1. A turpentine and resin extractor comprising a cylinder having a heating chamber at its base provided with a valve outlet, a perforated cage disposed within said cylinder and arranged in spaced relation thereto, to provide a surrounding space for the discharge of the volatile products, and a bottom space above said heating chamber for the reception of the resin, a valved outlet communicating with the said surrounding space, a vertical steam pipe disposed within the cage, a valved supply pipe leading externally through the cylinder and cage, and

connected with said vertical pipe, and a steam supply pipe leading laterally into the vapor discharge space and extending downward and communicating at its lower end with the heating chamber.

2. A turpentine and resin extractor comprising a cylinder having spaced bottom heads forming a heating chamber provided with a valved outlet, trunnions at diametrically opposite sides of the cylinder, a perforated cage arranged within said cylinder and spaced therefrom to provide a surrounding vapor discharge space and a bottom resin collecting space, valved outlets communicating with said spaces, a perforated pipe arranged vertically within the cage, a solvent supply pipe arranged within the top of the cage, steam supply pipes communicating respectively with the heating chamber and perforated vertical pipe, said steam supply pipes having end portions projecting outwardly at diametrically opposite sides of the cylinder through said trunnions, supporting bearings in which said trunnions are journaled, and valved steam conducting pipes extending into said bearings and communicating with said steam supply pipes.

3. A turpentine and resin extractor comprising a cylinder having a heating chamber at the bottom thereof, said heating chamber being provided with a valved outlet, a perforated cage disposed within the cylinder and spaced therefrom to provide a sur-

rounding vapor discharge space and a bottom resin collecting space, said spaces having valved outlets, a vertical steam pipe disposed within the cage, bearings in which the cage is pivoted to tilt, conducting pipes leading through said bearings and communicating respectively with the heating chamber and perforated pipe, valved supply pipes communicating with said conducting pipes, a union connecting said supply pipes and a main supply pipe connected with the union.

4. A turpentine and resin extractor comprising supporting bearings, a cylinder mounted upon horizontal axes to tilt upon said supporting bearings, said cylinder being provided with a heating chamber at its bottom having a valved outlet, a perforated cage disposed within the cylinder and spaced therefrom to provide a surrounding vapor discharge space and a bottom resin collecting space, said spaces having valved outlets, a vertical perforated pipe disposed within the cylinder, and steam supply pipes extending through the respective axes of the cylinder and communicating with the heating chamber and perforated pipe.

In testimony whereof I affix my signature in presence of two witnesses.
